UNITED STATES PATENT OFFICE.

MORITZ FICHTENBERG, OF MILWAUKEE, WISCONSIN.

DESIGN FOR A BICYCLE-FRAME.

SPECIFICATION forming part of Design No. 30,819, dated May 16, 1899.

Application filed April 20, 1899. Serial No. 713,786. Term of patent 3½ years.

To all whom it may concern:

Be it known that I, MORITZ FICHTENBERG, a citizen of the United States, residing at Milwaukee, county of Milwaukee, and State of Wisconsin, have invented and produced a new and original Design for Bicycle-Frames, of which the following is a specification, reference being had to the accompanying drawings, forming a part thereof, in which—

Figure 1 is a side view of a bicycle-frame to which my invention is applied. Figs. 2 and 3 are cross-sectional views of one of the rear stays, drawn, respectively, on lines *x x* and *y y* of Fig. 1. Figs. 4 and 5 are cross-sectional views of one of the arms of the front fork, drawn, respectively, on lines *t t* and *u u* of Fig. 1.

As shown in the drawings, the leading or material features of my design consist in the contrasting angular and oval shape of the fork-arms and stays, the ends *A* and *B* of the fork and stay arms, respectively, being oval, as illustrated, with a central oval portion *C* of less diameter than the end portions and intermediate angular portions *D*, with a central ridge *E*. The inner surface *F* of each of

the rear stays and rear-fork arms is flat, as shown in Figs. 2 and 3, while the inner surface *G* of the front-fork arms is rounded or semioval in shape, as illustrated in Figs. 4 and 5. The angular portion *D* at the lower end of the front fork is not terminated by an oval portion, but by a flattened extension *H*, as illustrated in Fig. 1. In all of the fork-arms or stays the ridge *E* is in the same plane with the oval end portions *A* and *B*, respectively, so that the central oval *C* appears in the form of a contraction or rounded depression, such as would be formed in an elastic body by a band wound tightly thereon.

Having thus described my invention, what I claim as new, and desire to secure by Letters Patent, is—

The design for a bicycle-frame as herein shown and described.

In testimony whereof I affix my signature in the presence of two witnesses.

MORITZ FICHTENBERG.
